UNITED STATES PATENT OFFICE.

MORAL O. SHRINER, OF NIAGARA FALLS, NEW YORK, ASSIGNOR TO SALINA A. SHRINER, OF NIAGARA FALLS, NEW YORK.

ASH SIFTER.

Application filed June 24, 1922, Serial No. 570,549. Renewed August 4, 1923.

To all whom it may concern:

Be it known that I, MORAL O. SHRINER, a citizen of the United States, residing at Niagara Falls, in the county of Niagara and State of New York, have invented new and useful Improvements in Ash Sifters, of which the following is a specification.

This invention relates to household devices, particularly to ash sifters and has for its object the provision of a novel device by means of which ashes may be sifted in a rapid and efficient manner without the annoyance of the clouds of dust which usually arise when devices of this character are operated.

An important object is the provision of a novel dustless ash sifter which is so constructed as to receive an ash pan which may be within a furnace or other stove and thereby render it unnecessary to pour the ashes from any receptacle into the device or to go through with any shoveling operation.

An additional object is the provision of a device of this character which will be simple and inexpensive in manufacture, easy to control and operate, efficient and durable in service and a general improvement in the art.

With the above and other objects and advantages in view the invention consists in the details of construction to be hereinafter more fully described and claimed and illustrated in the accompanying drawings in which:

Figure 1 is a side elevation of my device in applied position upon an ash can,

Figure 2 is a front elevation,

Figure 3 is a vertical cross section with the parts in initial position,

Figure 4 is a similar view showing the tray holder inverted,

Figure 5 is a horizontal section showing the shaking action,

Figure 6 is a longitudinal section,

Figure 7 is a perspective view of the rotary and slidale element.

Referring more particularly to the drawings, the letter A designates an ash can in conjunction with which my device is used though of course it should be understood that my device might be mounted upon some other type of receptacle if preferred.

In carrying out my invention I provide a casing 10 which is here shown as being more than semicylindrical and including parallel

sides 11, a curved top 12 and a bottom 13 having a central opening 14 surrounded by a depending flange 15 within which is a horizontal flange 16. This casing is designed to be mounted upon the top of the ash can A with the flange 16 engaged upon the upper edge of the can and with the flange 15 embracing the can. The material from which this casing and the parts to be described are formed is capable of variation though as a matter of fact galvanized iron will be found to be most satisfactory. The casing has one end closed by a wall 17 which is stationary while the opposite end wall 18 is formed with a rectangular opening 19 normally closed by a vertically swingable door 20 adapted to be held shut by a latch 21 slideable in a guide 22.

Mounted within this casing is a combined sieve and tray holder which includes a rectangular box 23 having one side covered by wire screen 24 of suitable mesh and which has its opposite side open. The opposite edges of the open side of this box 23 are formed with lateral extensions 25 on which are formed side members 26 which terminate in inwardly directed flanges 27. Secured on the flanges 27 are bowed leaf springs 28 for a purpose to be described.

This structure just described is supported within the casing 10 by means of a rod 29 which is rigidly secured at substantially the center of the end wall 17 and upon which is engaged a sleeve 30 which is rotatable and slideable thereon and which is fixed to the box 23 as shown. This sleeve 30 extends through a suitable hole in the forward end wall 18 and has its projecting end formed with a rectangular loop 31.

The portion of the device formed by the elements 25, 26 and 27 constitutes holding means for a rectangular tray 32 having a foldable bail 33 and a handle 34. This tray may be used as an ash pan in a stove or furnace and when shifting of the ashes is to be done this tray is capable of being slid into its holder formed by the parts 25, 26 and 27.

Mounted upon the end wall 18 near one end of the opening 19 therein is a loop 35 which is opposite the loop 31 and which is designed to have inserted therethrough an elongated lever 36.

The operation of the device is as follows:

Assuming that the tray 32 has been used as an ash pan in a stove or furnace and

that it is full of ashes which it is desired to sift and also assuming that the casing 10 is seated upon an ash can A, in order to effect sifting action, the operator passes the 5 lever 36 through the loops 31 and 35 when the combined tray holder and sieve is in such position that the screen is at the top thereof. The latch 21 is moved to inoperative position and the door 20 is open. The 10 operator then handles the tray by means of the bail 33 and handle 34 and slides the tray through the opening 19 and onto the springs 28 carried by the flanges 27, after which the door 20 is closed and refastened. 15 The lever 36 is then pulled out of the loop 31 which will permit the combined sieve and tray holder to turn over into such position that the screen will be lowermost. The lever 36 is then re-engaged within the 20 loop 31 and the operator grasps the other end of the lever and moves it back and forth which will obviously result in imparting reciprocatory movement to the sieve. This agitation will result in thorough sift- 25 ing of the ashes, so that all the small matter will pass through the sieve while the good or unburnt coal will remain thereon. The lever 36 is then disengaged from the 30 of 180° to again invert the tray holder and sieve which will result in causing all the cinders to fall again into the tray. When the door 19 is subsequently opened the tray may be withdrawn through the opening 19 and it will be found that by waiting a few 35 minutes opportunity will be given for all the dust to settle. The springs 28 operate to hold the tray firmly in position so that it cannot rattle about or become displaced during the reciprocatory movement of the 40 sieve and tray holder.

From the foregoing description and a study of the drawings it will be apparent that I have thus provided a simply constructed and consequently inexpensive de-

vice by means of which ashes may be sifted 45 in a very simple and easy manner and without the usual annoyance of having dust fly all over everything. Owing to the simplicity of the construction and the fewness of the parts it is apparent that there is 50 nothing at all to get out of order so that the device should operate most efficiently and have a long life.

While I have shown and described the preferred embodiment of the invention it 55 is of course to be understood that I reserve the right to make such changes in the form, construction and arrangement of parts as will not depart from the spirit of the invention or the scope of the subjoined claim. 60

Having thus described my invention I claim:

In an ash sifter, a hood adapted for engagement upon the top of an ash can, a stationary rod extending across the intermediate portion of said hood, a casing located within the hood and carrying a tubular member secured thereto and slidable upon said rod, said casing including a relatively small portion having one side open 65 and covered with wire screen, the casing further including a relatively large portion connected with the small portion by a wall and having its side opposite said screen 70 partially open, an open topped tray removably mounted within the larger portion of said casing with its open side disposed toward said screen, elongated bowed springs 75 within the partially open side of said casing engaging the bottom of the tray for holding the same against the wall connecting the two portions of the casing, and means for inverting and reciprocating said casing.

In testimony whereof I affix my signature. 80

MORAL O. SHRINER.
